CLAIM

The ornamental design for a portion of a cocktail cooler, as shown and described.

DESCRIPTION

FIG. 1 is a top perspective view of a portion of a cocktail cooler, showing our new design, shown in an environmental use;

FIG. 2 is a front view thereof, shown in an environmental use;

FIG. 3 is a rear view thereof, shown in an environmental use;

FIG. 4 is a left side view thereof, shown in an environmental use;

FIG. 5 is a right side view thereof, shown in an environmental use;

FIG. 6 is a top plan view thereof, shown in an environmental use;

FIG. 7 is a bottom view thereof, shown in an environmental use;

FIG. 8 is a front perspective view thereof, shown without the cooler in an environmental use, in enlarged scale;

FIG. 9 is a front view thereof, shown without the cooler in an environmental use, in enlarged scale;

FIG. 10 is a rear view thereof, shown without the cooler in an environmental use, in enlarged scale;

FIG. 11 is a left side view thereof, shown without the cooler in an environmental use, in enlarged scale;

FIG. 12 is a right side view thereof, shown without the cooler in an environmental use, in enlarged scale;

FIG. 13 is a top plan view thereof, shown without the cooler in an environmental use, in enlarged scale;

FIG. 14 is a bottom plan view thereof, shown without the cooler in an environmental use, in enlarged scale; and,

FIG. 15 is a cross-sectional view, taken along the line 15-15 of FIG. 6, shown in an environmental use.

(Continued)

The broken lines in the figures illustrate portions of the portion of a cocktail cooler that form no part of the claimed design.
